UNITED STATES PATENT OFFICE

MAX SHEROVER, OF NEW YORK, N. Y., ASSIGNOR TO INTERNATIONAL MERCHANTISING
SYNDICATE, INC., OF NEW YORK, N. Y., A CORPORATION OF NEW YORK

DESIGN FOR A MATTRESS COVERING OR SIMILAR ARTICLE

Application filed June 29, 1929. Serial No. 31,885. Term of patent 3½ years.

To all whom it may concern:

Be it known that I, MAX SHEROVER, a citizen of the United States, and a resident of New York, county and State of New York, have invented a certain new, original, and ornamental Design for Mattress Coverings or Similar Article, of which the following is the specification, reference being had to the accompanying drawing, forming part thereof.

The figure is a plan view of a mattress covering showing my new design.

I claim:

The ornamental design for a mattress covering or similar article substantially as shown.

MAX SHEROVER.
